Patented Mar. 4, 1969

213,447

HOUSING FOR AN AUTO STEREO UNIT

Randall C. Small, 7650 Balboa Blvd.,
Van Nuys, Calif. 91406

Filed Dec. 7, 1967, Ser. No. 9,697

Term of patent 14 years

U.S. Cl. D26—14
Int. Cl. D6—01

FIG. - 1

FIG. - 2

FIG. - 3

FIG. - 5

FIG. - 6

FIG. - 4

FIG. - 7

FIG. 1 is a perspective view of the housing for an auto stereo unit embodying my new design;

FIG. 2 is a front view thereof;

FIG. 3 is a right side view thereof;

FIG. 4 is a left side view thereof;

FIG. 5 is a bottom view thereof;

FIG. 6 is a plan view thereof;

FIG. 7 is a back view thereof.

The essential features of my design reside in those portions shown in full lines on the drawings.

I claim:

The ornamental design for a housing for an auto stereo unit, as shown and described.
